(Cl. D58—12)

To all whom it may concern:

Be it known that we, William F. Wise, a citizen of the United States, residing at Detroit, in the county of Wayne and State of Michigan, and Leonard A. Fannon, a citizen of the United States, residing at Detroit, in the county of Wayne and State of Michigan, have invented a new, original, and ornamental Design for a Container for Bottles and Other Articles, of which the following is a specification, reference being had to the accompanying drawings, forming a part thereof, wherein

We claim:

The ornamental design for a container for bottles and other articles, substantially as shown.

WILLIAM F. WISE.

LEONARD A. FANNON.
